(57) **CLAIM**

The ornamental design for front lights of a motor vehicle as shown and described.

DESCRIPTION

FIG. 1 depicts an elevation view of front lights of a motor vehicle according to a first variant of the design;

FIG. 2 depicts an elevation view of front lights of a motor vehicle in an alternate state;

FIG. 3 depicts an elevation view of front lights of a motor vehicle in an alternate state; and,

FIG. 4 depicts an elevation view of front lights of a motor vehicle in an alternate state.

The broken lines illustrate portions of the motor vehicle that form no part of the claimed design.

The cross-hatched and stippled shading in the drawings represents illumination of the front lights of a motor vehicle. The illumination represented by the cross-hatched shading is not limited to any particular color. The illumination represented by the stippled shading represents the color white.
